(57) **CLAIM**

The ornamental design for a flying insect trap, as shown and described.

DESCRIPTION

FIG. 1 is a right front perspective view of a first variant of a flying insect trap;

FIG. 2 is a top plan view of the flying insect trap of FIG. 1; FIG. 3 is a bottom plan view of the flying insect trap of FIG. 1;

FIG. 4 is a front elevational view of the flying insect trap of FIG. 1;

FIG. 5 is a rear elevational view of the flying insect trap of FIG. 1;

FIG. 6 is a left side elevational view of the flying insect trap of FIG. 1;

FIG. 7 is a right side elevational view of the flying insect trap of FIG. 1;

FIG. 8 is a right front perspective view of a second variant of a flying insect trap;

FIG. 9 is a top plan view of the flying insect trap of FIG. 8; FIG. 10 is a bottom plan view of the flying insect trap of FIG. 8;

FIG. 11 is a front elevational view of the flying insect trap of FIG. 8;

FIG. 12 is a rear elevational view of the flying insect trap of FIG. 8;

FIG. 13 is a left side elevational view of the flying insect trap of FIG. 8; and,

FIG. 14 is a right side elevational view of the flying insect trap of FIG. 8.

The broken lines shown in the drawings illustrate portions of the flying insect trap that form no part of the claimed design.
